UNITED STATES PATENT OFFICE.

WALTER S. PAYNE, OF UNIVERSITY PLACE, NEBRASKA.

POWER-OPERATED HAMMER.

1,158,270.

Specification of Letters Patent. Patented Oct. 26, 1915.

Application filed March 23, 1915. Serial No. 16,389.

To all whom it may concern:

Be it known that I, WALTER S. PAYNE, a citizen of the United States, residing at University Place, in the county of Lancaster and State of Nebraska, have invented certain new and useful Improvements in Power-Operated Hammers, of which the following is a specification.

My invention relates to improvements in power operated hammers of the reciprocatory type.

An important object of the invention is to provide apparatus of the above mentioned character, formed of parts which are readily separable for the purpose of cleaning and repairing them.

A further object of the invention is to provide apparatus of the above mentioned character, which is strong, and durable.

Other objects and advantages of the invention will be apparent during the course of the following description.

In the accompanying drawings forming a part of this specification and in which like numerals are employed to designate like parts throughout the same, Figure 1 is a central longitudinal sectional view through apparatus embodying my invention, Fig. 2 is a transverse section taken on line 2—2 of Fig. 1, and, Fig. 3 is a side elevation of the coupling-plug.

My improved hammer comprises a preferably cylindrical casing 5, formed of detachable casing sections 6 and 7, arranged in end to end relation, as shown. The forward casing section 7 preferably has a portion of its surface milled, as shown at 8. The casing section 7 is provided at its forward end with a reduced guide sleeve 9, receiving a reciprocatory tool or chisel 10. This tool or chisel is preferably provided with a longitudinal groove or recess 11, receiving a screw 12, which prevents the tool from dropping out of the sleeve 9, as shown. The casing section 6 is provided at its rear end with interior screw-threads for engaging with an exteriorly screw-threaded annular flange 12', carried by a cap or head 13, serving to close the rear end of the casing section 6, as shown. This cap 13 is provided with a central aperture 14, as shown.

The numeral 15 designates a coupling-plug which is preferably cylindrical and provided with exterior screw-threads, as shown at 16, for engaging with interior screw-threads formed upon the adjacent ends of

the casing sections 6 and 7. In this manner the casing sections 6 and 7 are detachably and securely held together.

Mounted to reciprocate within the forward casing 7 is a plunger-hammer 17, the forward end of which is adapted to strike the rear end of the tool 10. This plunger-hammer is provided with preferably diametrically oppositely arranged arms 18, 85 preferably integral therewith, such arms being mounted to slide within longitudinal openings 19 formed in the plug 15, as shown. The plunger-hammer 17 is provided in its rear portion with an axially extending preferably cylindrical recess or cavity 20, receiving suitably stiff compressible and expandable coil spring or springs 21, the rear end of which is mounted within a recess 22, formed in the plug 15, as shown. The plunger-hammer is provided in its forward end with a screw-threaded opening 20', receiving a screw-threaded plug 21', having a head 22' which engages the spring or springs 21. At its forward end the plug 21' is provided with a transverse opening or notch 23' for receiving a suitable tool for turning it, passed through an opening 24'. The screw-threaded plug 21' is adapted to be locked against rotation by clamping screws 85 25'. The function of this screw-threaded plug is to adjust the tension of the spring or springs 21. Arranged within the opening or cavity 24' is a hard steel block 26' normally held in place by clamping screws 90 27' or the like. This hard steel block is disposed to impinge against the end of the tool 10, as shown.

The numeral 23 designates a rotatable driving shaft journaled in the aperture 14 95 in the cap 13. Rigidly mounted upon the driving shaft 23 is a thrust ring 24, slidably engaging with the head 13. The forward end of the driving shaft 23 extends into a recess 25 formed in the coupling-plug 15, 100 and engages therein a thrust ball bearing 26, as shown. It is thus apparent that the shaft 23 is free to rotate but cannot partake of perceptible longitudinal movement with relation to the casing 5. Slidably mounted 105 upon the driving shaft 23 is a reciprocatory cam 27 rigidly attached to the rear ends of the arms 18, as shown at 28. This cam is provided with an inclined surface 29 and a trip shoulder 30. The reciprocatory cam 27 110 is engaged and moved by a rotatable cam 31, having an inclined surface 32 and a trip

shoulder 33, as shown. The rotatable cam 31 is rigidly mounted upon the driving shaft 23 to be retained thereby. It is thus apparent that upon the rotation of the cam 31 in the direction of the arrow, the same will move the reciprocatory cam 27 rearwardly, which in turn draws the plunger-hammer 17 rearwardly thereby placing the spring or springs 21 under tension. When the trip 10 shoulders 30 and 33 come into alinement, the reciprocatory cam 27 is released, allowing the spring or springs 21 to quickly throw or move the plunger-hammer 17 forwardly for striking a blow upon the rear end of the 15 tool 10.

Rotation may be imparted to the driving shaft 23 by any suitable means, while I prefer to drive the same by an armature shaft 34 of a motor 35. The armature shaft 20 34 is connected with the driving shaft 23 to drive the latter by means of a coupling or chuck 36, having an opening to receive the shaft 23 and rigidly secured to the armature shaft 34.

25 The casing of the motor 35 is provided with a forwardly extending tubular portion 37, adapted to be inserted within a clamp comprising longitudinal halves 38, secured together by bolts (not shown) passing through bolt holes 39. The forward end of the clamp receives the rear end of the casing section 6, whereby the casing 5 is rigidly attached to the casing of the motor 35.

30 In operation, the rotation of the shaft 34 is imparted to the shaft 23, in turn rotating the cam 31. This cam causes the movement of the reciprocatory cam 27, which co-operates with the spring or springs 21 to effect 40 a reciprocatory movement of the plunger-hammer 17. This plunger-hammer impinges against the rear end of the tool 10 as is obvious. It is obvious that the casing section 6 may be readily removed from the clamp 45 halves 38, and the casing sections 6 and 7 unscrewed from the coupling-plug 15, whereby the several parts may be separated for the purpose of cleaning or repairing.

It is to be understood that the form of my 50 invention herewith shown and described is to be taken as a preferred example of the same, and that various changes in the shape, size, and arrangement of parts may be resorted to without departing from the spirit of the 55 invention or the scope of the subjoined claims.

Having thus described the invention, I claim:

1. In a hammer of the character described; forward and rear casing sections arranged in end to end relation; a coupling-plug arranged within the adjacent ends of the casing sections and serving to secure them together; a reciprocatory plunger-hammer mounted within the forward casing

section in advance of the coupling-plug; a compressible coil spring arranged between the forward end of the coupling-plug and the plunger-hammer; a driving rotatable shaft mounted within the rear casing section 70 and held therein against longitudinal movement; a reciprocatory cam slidably mounted upon the driving shaft and connected with the plunger-hammer; and a rotatable cam secured to the driving shaft to rotate therewith and engaging the first named cam. 75

2. In a hammer of the character described; forward and rear casing sections arranged in end to end relation; a coupling-plug arranged within the adjacent ends of 80 the casing sections for securing them together and provided with longitudinal openings; a reciprocatory plunger-hammer mounted within the forward casing section in advance of the coupling-plug and carrying rearwardly extending arms mounted to reciprocate in said openings; a compressible coil spring arranged between the coupling-plug and plunger-hammer; a driving shaft 85 rotatably mounted within the rear casing section; a reciprocatory cam slidably mounted upon the driving shaft and connected with the arms; and a rotatable cam secured to the driving shaft to turn therewith and engaging the reciprocatory cam. 90

3. In a hammer of the character described; an exteriorly screw-threaded coupling-plug having longitudinal openings formed therethrough; a forward casing section provided at its rear end with interior screw-threads to engage with the coupling-plug and provided at its forward end with a tool receiving member; a rear casing section provided at its forward end with interior screw-threads for engaging the coupling-plug; a plunger-hammer mounted to reciprocate within the forward casing section and provided with arms extending through the longitudinal openings; a compressible coil spring arranged between the coupling-plug and plunger-hammer; a driving shaft 100 rotatably mounted within the rear casing section; a reciprocatory cam mounted to slide upon the driving shaft and rigidly attached to the rear ends of said arms; and a 105 rotatable cam rigidly mounted upon the driving shaft and arranged in advance of the reciprocatory cam to operate it. 110

4. In a hammer of the character described; a rear casing section; a coupling-plug secured within the forward end thereof and projecting outwardly beyond the same for a substantial distance and having longitudinal openings and a substantially centrally arranged journal recess; a cap detachably connected with the rear end of the rear casing section and provided with a journal opening; a rotatable driving shaft arranged within the journal openings; a thrust element rigidly secured to the driv- 120 125 130

ing shaft and engaging with the cap; a reciprocatory cam slidably mounted upon the driving shaft; a rotatable cam rigidly mounted upon the driving shaft and arranged in advance of the reciprocatory cam; a plunger-hammer disposed in advance of the cams and having arms passing through the openings of the coupling-plug and secured to the reciprocatory cam; a compressible coil spring arranged between the plun-

ger-hammer and coupling-plug; and a forward casing receiving the plunger-hammer and engaging with the coupling-plug.

In testimony whereof I affix my signature in presence of two witnesses.

WALTER S. PAYNE.
